UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING MACHINE.

Application filed November 15, 1921, Serial No. 515,321. Renewed July 11, 1925.

Referring to the accompanying drawings: Figure 1 is a plan view of my improved mining machine.

Fig. 2 is an elevation thereof partly in section.

Fig. 3 is a plan view of an adaptation of my mining machine to arc wall operations.

Fig. 4 is an elevational view of the machine shown in Fig. 3.

10 Fig. 5 is a sectional elevation of one of the dislodging tools.

Fig. 6 is a sectional elevation taken on the line 6—6 of Fig. 5 looking in the direction of the arrows.

15 Fig. 7 is a sectional elevation taken on the line 7—7 of Fig. 5 looking in the direction of the arrows.

Fig. 8 is a detail view of part of the mechanism for adjusting the elevation of the uppermost and lowermost dislodging tools.

20 Fig. 9 is a sectional detail view of the multiple valve for controlling automatically the operation of the pneumatic hammer dislodging mechanism.

25 Fig. 10 is an enlarged view, partly in section, of the pneumatic pumping mechanism shown in Figs. 1 and 2.

Fig. 11 is an enlarged sectional view of Fig. 9 on the line 11—11 looking in the direction of the arrows; and

Fig. 12 is an enlarged sectional view of Fig. 9 on the line 12—12 looking in the direction of the arrows and showing in addition an end view of the compressed air storage tank.

30 In Figs. 1 and 2 is shown a base frame 13 adapted to rest on and slide over a mine floor along an upright mine wall. Rigidly connected to the base frame 13 and extending upwardly therefrom is a supporting frame 14 having one wall 15 parallel to the mine wall 17 or to the longitudinal length of the machine and having another wall 16 at right angles to such longitudinal length.

Secured rigidly to the forward end of the 40 upright wall 15 is a T-shaped auxiliary frame 18 having a horizontal elongated bar 19 of considerable strength extending angularly from the machine toward the mine wall as shown in Fig. 2. The bar or arm 19 is adapted 45 to occupy a position intermediate the floor and roof of the mine chamber and is provided

50 at its forward end with a dislodging tool 20. The latter is connected to the bar 19 as hereinafter described and comprises a pointed digging and splitting tool 21 and upper and lower scraping or trimming tools 22 and 23.

Also extending forward angularly from the supporting framework are the upper and lower arms 24 and 25 provided with the dislodging tools 26 and 27.

60 The dislodging tool 26 is connected to the arm 24 as hereinafter described and comprises a digging and splitting point 28 and a wall trimmer or scraper 29. Likewise the dislodging tool 27 is connected to the arm 25 as 65 hereinafter described and comprises a digging and splitting point 30 and a wall trimmer or scraper 31.

70 The uppermost and lowermost arms 24 and 25 are pivoted at 32 and 33 respectively to the upright wall 15 to permit adjustment in elevation of the dislodging tools 26 and 27. An additional standard 34 on the base frame 13 may be provided so as to support bearings for shafts keyed to the arms 24 and 25 75 and journaled in such bearings as well as in bearings in the upright wall 15.

Keyed to the shaft 32, as shown in Fig. 2, is an arm 35 which has a segmental worm gear 36 at its forward end to mesh with a worm 37 80 which is mounted in bearings on a vertical axis on the standard 38 extending upwardly from the rigid arm 19. By referring to Fig. 8 it will be seen that the worm 37 is keyed to a vertical shaft 41 which is journaled in the 85 bearings 39 and 40, extending horizontally from the standard 38. The upper end of the shaft 41 is squared at 42 to receive a turning tool so that the arm 24 may be lifted or lowered to adjust the height of the dislodging tool 26. In a similar manner the arm 25 may be lifted or lowered to adjust the elevation 90 of the dislodging tool 27, by operating the worm gear adjusting mechanism 43 which is connected to the arm 44.

95 Pivotedly connected at 45 to the supporting framework is a hydraulic motor 46 comprising a cylinder 47 and a piston 48. The latter is connected to the piston rod 49 which in turn is rigidly connected to the roof jack 100 comprising the cylinder 50 and the plunger 51. The cylinder 50 is provided with a shoe

52 for engaging the floor and the plunger 51 is provided with a shoe 53 for engaging the roof.

A valve 54 controls the supply of the liquid pressure from the supply pipe 56. By turning the valve 54 to the position shown in Fig. 2 by means of the handle 55, supply pressure is exerted from the pipe 56 into the cylinder 47 and also through the passage 57 in the center of the piston rod 49 into the cylinder 50. The exhaust pipe is shown at 58. When the valve 54 is moved to the position shown in Fig. 2 the roof jack will at once be anchored to form an abutment for the hydraulic motor 46 to act against. As the hydraulic pressure is continued the framework together with the dislodging tools are moved rectilinearly along the inner wall to very powerfully act on the coal to 20 dig into and split the same from the mine vein in one continuous forward movement.

After the hydraulic motor 46 has made a complete stroke the valve handle 55 should be turned to the right as shown in Fig. 2, 25 through an angle of about ninety degrees, so as to connect the supply pipe 56 to the cylinder 47 to the right of the piston 48 and so as to connect the space to the left of the piston 48 to the exhaust pipe 58. The roof jack will then be released and dragged to the left to a new location where it can again be anchored to form an abutment for another forward dislodging operation of the dislodging mechanism.

35 While the construction shown is such that dislodging operations may be secured by operating the motor 46 described, to give the dislodging tools continuous forward paths of travel, said construction is also such that hammer blows may be effected on the tools 20, 26 and 27 relatively to the arms 19, 24 and 25 which carry them. The preferred hammer blow mechanism is shown in Fig. 5 but it should be understood that various other 40 types of hammer blow mechanism may be used in the general combination, if desired. Each of the arms 24, 19 and 25 is provided with an individual hammer device such as that shown in Fig. 5.

50 Rigidly connected to the dislodging tool 26 and extending rearwardly therefrom is a plunger 59 as shown in Fig. 5. This plunger fits in a cylinder 60 and extends into a somewhat larger cylinder 61 along which is 55 adapted to reciprocate the hammer 62. At the right-hand end of the cylinder 61 as shown in Fig. 5 is a buffer 63 for cushioning the blow of the hammer 62 in its flight to the right and assisting to start it back again in the opposite direction. The pipe 64 conducts the compressed air into the cylinder 61 to the right of the hammer 62 and the pipe 65 and passageway 66 conduct the compressed air to the cylinder 61 to the left of the hammer 62, as viewed in Fig. 5.

The mechanism for automatically controlling the operation of the pneumatic hammer to secure reciprocation of the hammer 62 at a predetermined rate, is shown in Figs. 1, 2, 9, 10, 11 and 12. An electric motor 67 is mounted on a pedestal 68 secured to the base frame 13 and is connected by its motor shaft 71 to worms 69 and 70. The worm 69 meshes with the worm gear 72 pivoted at 73 to the pedestal 74, as shown in Figs. 2 and 10.

75 As shown in Fig. 10 a pitman 75 is connected between the worm gear 72 and the piston rod 76 of an air pump comprising the cylinder 78 and a piston 77 secured to said piston rod 76. When the motor 67 is operated to rotate the worm gear 72 the pump will be operated to alternately force air through the pipes 79 and 80 which are connected to the ends of the cylinder 78. When the piston moves down the check valve 81 automatically opens to permit intake of air and at the same time the check valve 82 automatically closes; also at the same time the check valve 83 automatically closes and the check valve 84 automatically opens to permit air to be forced from the cylinder 78 into the pipe 80. When the piston 77 is moved up the check valve 83 opens, the check valve 84 closes, the check valve 81 closes, and the check valve 82 opens; air is drawn into the cylinder 78 below the piston from the atmosphere and forced out of the cylinder above the piston into the pipe 79.

90 As shown in Fig. 2 the pipes 79 and 80 are connected to the compressed air tank 85 from which a pipe 86 leads to the valve controlling mechanism 87. Secured to the wall 15 are spaced-apart brackets 88 and 89 provided with circular openings 90 and 91 respectively for the ends of the cylindrical valve chest 92 (Fig. 9). Within the valve chest 92 is 95 mounted a cylindrical multiple valve 93 provided with several valve passages arranged for controlling the operation of the pneumatic hammers on the bars 24, 19 and 25.

100 Secured to the lower end of the drum valve 93 is a shaft 94 which carries a gear 95 in mesh with a pinion 96. The electric motor 67 has its motor shaft connected to a worm 98 which meshes with a worm wheel 99, the latter being connected to the pinion 96 to drive the same. When the electric motor 67 operates the drum valve 93 will be rotated.

105 By referring to Figs. 9, 11 and 12 it will be seen that the pipe 86 communicates with a vertical pipe 100 from which extend laterally the branch pipes 101, 102, 103, 104, 105 and 106 through the valve chest 92 to the 110 passages in the valve 93. On the front side of the valve chest 92 is a vertical pipe 107 which leads to the exhaust pipe 108 and is supplied with the branch pipes 109, 110, 111, 112, 113 and 114 which lead through the 115 valve chest to the valve passages.

120 The valve passages also communicate with 125

the lateral pipes 64, 65, 115, 116, 117 and 118 which lead to the pneumatic hammers on the bars 24, 19 and 25. When the valve 93 is in the position shown in Fig. 12 the pressure supply tank is connected by means of the pipes 86, 100 and 101 to the valve passage 119 and thence to the pipe 64 to drive the hammer 62 to the left as shown in Fig. 5, to strike a hammer blow against the plunger 59 and thus forcibly drive the dislodging tool 26 into the coal of the mine vein. At the same time the space to the left of the hammer 62 is opened to exhaust through the passageway 63, pipe 65, valve passageway 120 and pipes 110 and 107. Upon a quarter turn of the valve 93 in an anti-clockwise direction the passageway 121 will be connected between the pressure supply and the pipe 65 to cause the hammer 62 to fly to the right as viewed in Fig. 5 and then the pipe 64 will be connected to exhaust. If desired the controlling mechanism may be such that the middle dislodging tool 20 will be operated first by a hammer blow and then the roof dislodging tool 26 operated followed by the floor dislodging tool 27. In this manner the coal may first be loosened intermediate the floor and roof and then broken down more easily above and below. The valve control mechanism may also be such that all three dislodging tools are struck repeated hammer blows about simultaneously. It should be noted that while the valve 93 connects the supply pressure to the various pneumatic hammers in multiple the latter in reality operate independently of each other; that is to say, each pneumatic hammer may be operated whether the others are operated or not.

It may sometimes happen that one of the dislodging tools will split off a piece of coal while the others are still being operated to dislodge coal. I therefore prefer to provide a slide valve 122 (Fig. 5) for shutting off the ports for the pipes 64 and 65 when the dislodging tool moves out beyond a predetermined distance. As shown in Fig. 5 the valve 122 is connected by a bar 123 to a lug 124 extending into a longitudinal recess 125 in the tool 126. When the tool moves out beyond the desired distance the lug 124 will be engaged to cause the valve 122 to close the ports of the pipes 64 and 65. A limit stop 126 is provided to engage the guide 127 on the cylinder 61 to limit the outward movement of the valve 122. When the machine is moved along the coal face to a new position by operation of the valve 54 (Fig. 2) the tool 26 will again engage the coal at the mine wall whereupon the valve 122 will be automatically restored to open position. It will thus be seen that mechanism is provided for automatically stopping the pneumatic hammer when it has no work to do and for automatically restarting the same as soon as

it is called upon to dislodge coal from the face of the mine wall.

Whenever the dislodging tools are pressed against the coal they are started automatically and automatically kept in operation to dislodge the coal; such automatic operation of the dislodging tools is effected very quickly, efficiently and powerfully.

In Figs. 3 and 4 I have shown the machine of Figs. 1 and 2 applied to arc wall mining. Bolted to the base frame 13 at 128 and 129 are a radius rod or bar 130 and a connecting rod 131 which is bolted at 132 to the bar 130 intermediate the ends of the latter. The bar 130 is pivoted to the roof jack 133. Therefore, when the latter is anchored it serves as a fulcrum for the machine to swing about while in operation along an arcuate mine wall 134.

A rear abutment may be provided in the form of a roof jack 50. A motor 46 is pivoted at 45 to the rear end of the base frame 13. The interior arrangement of the roof jack 50 and of the motor 46, as well as the control mechanism may be as shown at the right hand end of Fig. 2. It will thus be seen that while the pneumatic hammers are operating the dislodging tools may be fed to their work along an arcuate mine wall and at intervals the abutment 50 may be moved forward to a new position and reanchored and the motor 46 again operated to feed the dislodging tools to their work. After the machine has been operated along an arc of about 180° the roof jack 133 may be moved forward and the machine positioned for another arc wall operation in the manner above described.

What I claim and desire to have protected by Letters Patent in the United States is:

1. In a mining machine, the combination with a supporting frame, of an elongated supplemental frame pivoted to said supporting frame to extend forwardly therefrom, a pneumatic dislodging tool provided with hammer blow mechanism and mounted on said supplemental frame to move bodily therewith horizontally along an upright mine wall, means comprising worm gearing for adjusting said supplemental frame relative to said supporting frame to vary the elevation of said dislodging tool, said worm gearing holding said supplemental frame rigidly connected to said supporting frame in adjusted relative position, and means for moving said frames together with said dislodging tool bodily and horizontally along such upright mine wall to effect feeding of said dislodging tool.

2. In a mining machine, the combination with a supporting frame, of a plurality of spaced-apart elongated dislodging tools each extending in a general horizontal direction and each adapted to penetrate the coal in its

native bed and by wedging action split apart the coal from the unmined mass in comparatively large pieces, means for operating the dislodging tools rectilinearly relatively to said supporting frame, and means for exerting sufficient force to move said supporting frame together with the dislodging tools mounted thereon in the direction of the mine vein to effect by such bodily movement without such relative movement of said tools dislodgment of the coal in large pieces over an area extending from the floor to the roof of the mine chamber in one operation.

3. In a mining machine, the combination with a supporting frame, of a plurality of spaced-apart elongated arms mounted on said frame, a plurality of pointed wedging tools one on each of said arms and each adapted to rectilinearly penetrate the coal in its native bed and by wedging action split and tear the coal from the face of the mine vein over a wide area, means for operating said tools relatively to said arms, and means for moving said frame along the mine vein.

25 4. In a longwall mining machine, the combination with a supporting frame adapted to move along a mine wall substantially parallel to the face thereof, dislodging mechanism mounted on said frame to move bodily therewith and comprising means to penetrate the coal at the face of the mine wall and rip and tear the same from the unmined mass over an area extending over substantially the entire face, fluid pressure hammer-blow mechanism for operating said dislodging mechanism relatively to said supporting frame, and means for moving the supporting frame rectilinearly along the working face substantially parallel thereto to effect feeding of the dislodging mechanism in the direction of the mine vein and substantially parallel to the working face to enable said dislodging mechanism to split and tear the coal from the face of the mine vein over a wide area and in large pieces.

5. In a mining machine, the combination with a base frame adapted to rest on and slide over a mine floor, of dislodging mechanism mounted on said frame to move bodily therewith and comprising a plurality of spaced-apart penetrating tools each adapted to penetrate the coal and cooperate with the other dislodging tools to split and tear the coal from the face of the mine vein over a wide area extending from the floor to the roof of the mine chamber, fluid pressure hammer-blow mechanism for operating said dislodging tools relatively to said frame, and means for moving the latter along the mine wall to effect feeding of said dislodging mechanism along a path substantially parallel to the mine wall.

6. In a mining machine, the combination with a supporting frame, of dislodging mechanism mounted thereon and comprising

ing a plurality of cooperating penetrating tools adapted to split and tear the coal from the face of the mine vein in large pieces extending over the entire working face, fluid pressure hammer-blow mechanism for operating said dislodging mechanism, an abutment, and means connected between said abutment and said frame for moving the latter to feed said dislodging mechanism along the mine wall and substantially parallel thereto.

7. In a mining machine, the combination with a supporting frame, of a supplemental frame extending therefrom in a general horizontal direction, a plurality of dislodging tools mounted on said supplemental frame in spaced-apart positions extending from the floor to the roof of the mine chamber and for reciprocatory movement relatively to said supplemental frame, fluid pressure hammer-blow mechanism for simultaneously operating said dislodging tools, and means for simultaneously feeding said dislodging tools along the mine wall to effect dislodgment of the material from the mine wall along the entire face thereof.

8. In a mining machine, the combination with a supporting frame, of a supplemental frame mounted thereon, a plurality of spaced-apart dislodging tools mounted on said supplemental frame each for a limited movement relatively thereto and in position for simultaneous operation each to penetrate the mine wall and each to cooperate with the others to dislodge the material by wedging and splitting action in large pieces over a wide area of the working face, fluid pressure hammer-blow mechanism for operating said dislodging tools simultaneously, and means for moving the supporting frame along the mine chamber to secure simultaneous feeding movement of all of said dislodging tools along the mine wall in a general horizontal direction to effect dislodgment of the material in large pieces over a wide area of the working face.

9. In a mining machine, the combination with a supporting frame, of a plurality of spaced-apart dislodging tools each adapted to penetrate the coal in its native bed and by wedging action split and tear the coal from the unmined mass, means for supporting said tools on said frame in an upright series for action on an upright coal face, a plurality of fluid pressure hammer-blow mechanisms one provided for each of said dislodging tools to move the latter relatively to said supporting frame, and means for effecting feeding movement of the dislodging tools in the direction of the mine vein to effect dislodgment of the coal from the upright mine wall over an area extending from the floor to the roof of the mine chamber.

10. In a mining machine, the combination

- with a supporting frame, of a plurality of spaced-apart dislodging tools each adapted to penetrate the coal in its native bed and by wedging action split and tear the coal from the unmined mass over a wide area, fluid pressure hammer-blow devices for the respective dislodging tools, and means for effecting feeding movement of the dislodging tools along the mine wall to enable said dislodging tools to dislodge the coal over an area extending from the floor to the roof of the mine chamber.
11. In a mining machine, the combination with a supporting frame, of a supplemental frame pivotally connected thereto for bodily movement therewith, a dislodging tool mounted on said supplemental frame and adapted to penetrate the coal in its native bed and by wedging action split and tear the coal from the unmined mass, worm gearing mechanism for swinging said supplemental frame on its pivotal connection to said supporting frame to adjust the elevation of said dislodging tool, fluid pressure hammer-blow mechanism for driving said dislodging tool, relatively to said supplemental frame, and means for moving the supporting frame, supplemental frame and dislodging tool to effect feeding movement of the latter to cause said penetrating tool to rip and tear the coal from the face of the mine vein over a wide area relatively to said tool and thereby cause the coal to be dislodged in large pieces.
12. In a mining machine, the combination with a main frame, of a supplemental frame rigidly connected thereto, a dislodging tool mounted on said supplemental frame to move bodily therewith, an upper swinging frame pivotally connected to said supporting main frame, an additional dislodging tool mounted on said upper swinging frame to move bodily therewith, means for swinging said upper frame to adjust the elevation of the dislodging tool mounted thereon and hold said upper frame rigidly connected to said main frame, means for driving said dislodging tools individually while occupying spaced-apart positions but cooperating with each other to dislodge large pieces of material from the mine vein, and means for moving the main frame to effect feeding movement of the said dislodging tools.
13. In a mining machine, the combination with a main frame, of a supplemental frame connected thereto to move bodily therewith, a dislodging tool mounted on said supplemental frame to move bodily therewith and comprising a pointed wedging member adapted to penetrate the mineral in its native bed and by rectilinear feeding movement tear the mineral from the mine vein over a wide area above and below the point of application of the tool, a lower swinging frame for adjustment but rigid with said main frame for bodily movement therewith, an additional dislodging tool having a similar pointed penetrating wedging member mounted on said lower frame to move bodily therewith, means for adjusting said lower frame to vary the elevation of the dislodging tool mounted thereon, and means for operating both of said dislodging tools including feed thereof by movement of the machine along the mine vein.
14. In a mining machine, the combination with a main frame, of a dislodging tool mounted on said frame for bodily movement therewith in a general horizontal direction along the mine wall intermediate the floor and roof of a mine chamber, an additional dislodging tool mounted on said frame for movement along said mine wall at or adjacent the roof of the mine chamber, another dislodging tool mounted on said frame for movement along said mine wall at or adjacent the floor of the mine chamber, means for independently adjusting the elevation of the dislodging tools adjacent the floor and roof respectively, each of said dislodging tools comprising a pointed wedging member adapted to penetrate by rectilinear movement the mineral in its native bed and by wedging action rip and tear the mineral from the unmined mass over wide areas at the working face, and means for effecting the operation of the dislodging tools by imparting rectilinear movements thereto to dislodge the face of the mine vein between the floor and roof of the mine chamber.
15. In a mining machine, the combination with a supporting frame, of a plurality of spaced-apart dislodging tools mounted on said supporting frame in position to cooperate with each other to dislodge the whole face of the mine vein, each tool comprising a pointed penetrating wedging member adapted to receive rectilinear movement to rip and tear the mineral from the face of the mine vein over a wide area, means for adjusting the elevations of the uppermost and lowermost dislodging tools in accordance with the thickness of the mine vein or the height of the mine chamber, and means for operating said dislodging tools including movement of the supporting frame along the mine wall in a general horizontal direction.
16. In a mining machine, the combination with a main frame, of a supplemental frame mounted thereon to move bodily therewith, a plurality of spaced-apart penetrating dislodging tools each adapted to rip and tear the material from the face of the mine vein over a wide area, means for mounting said tools in an upright series on said frame in position to co-operate to dislodge the mineral from the upright working face in large pieces over substantially the entire area of such working face, fluid pressure hammer-blow mechanism for driving said dislodging tools, means for controlling the operation of said hammer-

blow mechanism, and means for moving the main frame together with the supplemental frame and said dislodging tools bodily to effect feeding movement of the dislodging tools and the step by step re-positioning thereof for the dislodgment of the material over a wide area of the working face in large pieces.

17. In a longwall mining machine, the combination with a supporting frame, of dislodging mechanism mounted thereon in position to penetrate coal in its native bed and by wedging action split and tear the coal from the face of the mine vein over an area 15 extending from the floor to the roof of the mine chamber, fluid pressure hammer-blow mechanism for operating said dislodging mechanism relatively to said supporting frame, and means for moving the supporting 20 frame and dislodging mechanism bodily along the working face rectilinearly to effect feeding of the dislodging mechanism.

18. In a mining machine, the combination with a supporting frame, of a dislodging 25 tool mounted thereon for bodily movement therewith and for an operating movement relatively thereto and adapted to penetrate coal from a mine vein along an upright mine wall to dislodge such coal, fluid pressure hammer blow mechanism for operating said dislodging tool by movement relatively to said supporting frame while such tool engages the coal at the mine wall, automatic mechanism for rendering inoperative said hammer-blow 30 mechanism when said dislodging tool moves outwardly beyond a predetermined position relative to said supporting frame and for automatically rendering said hammer-blow mechanism operative when said tool again 35 engages the mine wall, and means for moving said supporting frame together with the dislodging tool bodily along the mine wall in the direction of the mine vein and effect feeding of the dislodging tool.

40 19. In a mining machine, the combination with a supporting frame, of a pump mounted thereon, a pressure tank, a plurality of dislodging tools, hammer blow mechanism for operating said dislodging tools, a multiple controlling valve connected to said hammer blow mechanism and to said pressure tank, and a motor for operating said pump and at the same time operating said valve to effect the operation and control of said dislodging 45 tools.

50 20. In a mining machine, the combination with a supporting frame, of dislodging mechanism mounted thereon in fixed relation thereto and comprising mechanism for penetrating the coal in its native bed and by wedging action split and tear the coal from the unmined mass, fluid pressure hammer-blow mechanism for operating said dislodging mechanism, and means for feeding said dislodging mechanism rectilinearly along 55

the coal vein to effect dislodgment of the coal over an area extending from the floor to the roof of the mine chamber while said dislodging mechanism remains in such fixed relation.

21. In a mining machine, the combination 70 with a supporting frame, of dislodging tools mounted thereon and adapted to penetrate an upright mine wall at spaced apart points to tear material therefrom across the space between the floor and the roof of the mine 75 chamber, powerful feeding mechanism for forcing said dislodging tools along the mine wall to tear the material therefrom as aforesaid, hammer-blow mechanism for actuating said tools and an anchored pivot and connections for directing said dislodging tools along an arcuate mine wall.

22. In a mining machine, the combination with a roof jack, of a mining machine connected thereto to swing about said roof jack 85 on an upright axis, an additional roof jack adapted to act as an abutment, a motor connected between said abutment and the mining machine to push the latter along an arcuate mine wall, and means for operating said 90 mining machine during the arcuate feeding movement thereof effected by said motor.

23. In a mining machine, the combination with a supporting frame, of a plurality of spaced-apart pointed wedging tools mounted 95 on said frame in an upright series in position for distribution across the mine vein, means for actuating said tools individually by projecting them rectilinearly relatively to said supporting frame to cause the same to rip or tear the mineral adjacent the tools and between the same from the mine vein over an area extending across the working face, and means for moving the supporting frame along the working face step by step to new 100 positions for the actuation of said tools.

24. In a mining machine, the combination with a supporting frame, of dislodging mechanism mounted thereon in position to slice off a layer of coal from an upright face 110 of a mine vein, automatic hammer-blow mechanism for operating said dislodging mechanism while said frame remains stationary by projecting such dislodging mechanism in the direction of travel of the machine, and means for positioning said frame to adjust the dislodging mechanism to its work at the mine wall to secure increments of such sliced layer along the working face.

115 25. In a mining machine, the combination with a portable frame, of dislodging mechanism mounted thereon to move bodily therewith and comprising an upright series of penetrating wedging tools adapted to cooperate to slice off the face of the mine vein, means for confining movement of said frame along a predetermined path, hammer-blow mechanism for actuating said tools, and means for moving said frame along the face 120 of the mine vein while said frame is con- 125

fined to such predetermined path to hold the dislodging mechanism to its work.

26. In a mining machine, the combination with a supporting frame, of a plurality of spaced-apart dislodging tools each adapted to penetrate the mineral in its native bed and by wedging action split and tear such mineral from the unmined mass, means for mounting said dislodging tools in an upright series on said frame in position to operate on an upright working face of the mine vein, a plurality of fluid pressure hammer-blown mechanisms one provided for each of said dislodging tools, and means for effecting feeding movement of the dislodging tools in the direction of the mine vein.

27. In a mining machine, the combination with a supporting frame, of a plurality of spaced-apart dislodging tools each adapted to penetrate the coal in its native bed and by wedging action split and tear the coal from the unmined mass, a plurality of fluid pressure hammer-blown mechanisms one provided for each of said dislodging tools to move the latter relatively to said supporting frame, means for adjusting the elevation of the uppermost dislodging tool, and means for effecting feeding movement of the dislodging tools in the direction of the mine vein to effect dislodgment of the coal from an upright mine wall over an area extending from the floor to the roof of the mine chamber.

28. In a mining machine, the combination with a supporting frame, of a plurality of spaced-apart dislodging tools each adapted to penetrate the coal in its native bed and by wedging action split and tear the coal from the unmined mass over a wide area, means for adjusting the elevation of the lowermost tool, fluid pressure hammer-blown devices for the respective dislodging tools, and means for effecting feeding movement of the dislodging tools along the mine wall to enable said dislodging tools to dislodge the coal over an area extending from the floor to the roof of the mine chamber.

29. In a mining machine, the combination with a supporting frame, of dislodging mechanism mounted thereon and comprising upright multiple penetrating mechanism in fixed relation with said frame for penetrating the coal in its native bed and by wedging action split and tear the coal from the upright face of the mine vein, fluid pressure hammer-blown mechanism for operating said dislodging mechanism, and means for feeding said dislodging mechanism along a mine vein in a general horizontal direction while said multiple penetrating mechanism remains arranged uprightly in fixed relation to said supporting frame.

30. In a mining machine, the combination with a supporting frame, of a supplemental frame comprising tool supports spaced-apart in upright series and rigidly connected to

said supporting frame, dislodging mechanism mounted on said tool supports in position to penetrate the coal in its native bed and by wedging action split and tear the coal from the face of the mine vein in large pieces over a wide area, fluid pressure apparatus for operating said dislodging mechanism by reciprocating the same relatively to said supplemental frame, and means for effecting feeding of said dislodging mechanism.

31. In a mining machine, the combination with a supporting frame, of dislodging mechanism mounted uprightly thereon in position to penetrate the coal in its native bed over an area extending between the floor and roof of the mine chamber and by wedging action split and tear the coal from the face of the mine vein over an area extending from such floor to such roof, automatic fluid pressure hammer-blown mechanism for operating said dislodging mechanism relatively to said supporting frame, and means for moving the supporting frame and the dislodging mechanism bodily in a general horizontal direction along the mine vein to effect feed of the dislodging mechanism and position the latter for dislodging the coal from the floor to the roof in one operation in a general horizontal direction along the mine vein.

32. In a mining machine, the combination with a supporting frame, of dislodging mechanism mounted thereon and comprising superposed penetrating wedging tools arranged for simultaneous automatic operation relatively to the supporting frame to slice off a layer of coal from an upright mine wall, automatic means for operating said dislodging mechanism by projecting the tools individually relatively to the supporting frame along rectilinear lines while said supporting frame remains stationary, and means for positioning said supporting frame to adjust the dislodging mechanism to its work at the mine wall to secure automatically increments of dislodgment of such sliced layer.

33. In a mining machine, the combination with a portable frame, of means for confining said frame to movement along a predetermined path, dislodging mechanism mounted on said frame in fixed relation therewith and to move bodily therewith, said dislodging mechanism comprising penetrating wedging tools adapted to slice off the face of the mine vein, and automatic means for operating said dislodging mechanism including reciprocation of said tools and the movement of said frame along such predetermined path while said dislodging mechanism remains in fixed relation to said frame.

34. In a system of mining coal, a method which consists in piercing a solid upright face of a coal vein to penetrate the same deeply and dislodge the coal entirely by hammer-blown wedging action substantially back from the face at spaced-apart points in an

upright series and between the floor and the roof of the mine chamber to split the coal from the unmined mass in large pieces over a wide area by such piercing and hammer-blow wedging action at such spaced-apart points.

35. In a system of mining coal, a method which consists in simultaneously piercing the solid upright face of a coal vein to penetrate the same deeply and dislodge the coal entirely by hammer-blow wedging actions substantially back from the face at spaced-apart points in an upright series and between the floor and the roof of a mine chamber to split the coal from the unmined mass in large pieces over a wide area by such piercing and hammer-blow wedging action at such spaced-apart points.

36. In a system of mining coal, a method of mining coal from the solid of a mine vein, which consists in distributing a plurality of piercing wedging tools across the upright face of a mine vein and exerting hammer-blow forces on said tools continuously in the same direction to cause the same to move along the mine wall and exert concentrated intermittent pressure at the forward end thereof and by hammer-blow wedging action split and tear the coal in large pieces adjacent to and between the same over a wide area extending across the mine vein and with a minimum production of fine particles of coal.

37. In a system of mining coal, the method of mining coal from the solid of a mine vein without blasting which consists in deeply penetrating the solid face of the coal vein at spaced-apart points along an upright series and by hammer-blow wedging action producing cleavages spaced back from the coal face to dislodge the coal over an extended area and in large lumps with a minimum production of fine particles of coal.

38. In a system of mining coal directly from a solid face of a mine vein, a method which consists in applying a plurality of pointed wedging tools distributed in an upright series in spaced-apart relation across the entire working face of the mine vein and exerting hammer-blow forces on said tools along paths each extending in a general horizontal direction along the mine vein to cause them to penetrate deeply the solid face of the coal vein and split the coal in large pieces from such face over an area extending entirely across the mine vein.

39. In a system of mining coal directly from the solid face of a mine vein, the method which consists in distributing in an upright series the application of continuously forward and intermittently acting hammer-blow forces to deeply penetrate the coal face and by wedging action tear away and slice off coal from such face over a wide area to secure

large pieces of coal with fine particles reduced to a minimum.

40. In a system of mining coal directly from the solid face of a mine vein, the method which consists in distributing pointed wedging tools, one at the corner between the roof and the upright working face and another at the corner between the floor and the upright working face and another intermediate the floor and the roof at the upright working face, associating trimming tools with said pointed wedging tools, and applying forwardly acting forces to each of said tools individually to cause the pointed wedging tools to penetrate deeply the solid face of the mine vein and by wedging action split and tear the coal in large pieces adjacent the tools and between the same over an area extending entirely across the working face of a mine vein while the tools associated with said pointed wedging tools trim off the projections.

41. In a system of mining coal directly from a solid face of a mine vein, the method which consists in distributing a plurality of sharpened wedging tools entirely across the working face each tool being adapted to penetrate deeply the solid coal and by wedging action split and tear large pieces of coal from the unmined mass with a minimum production of fine particles of coal, distributing trimming tools at the roof and at the floor of the mine chamber, applying hammer-blow forces to all of said tools to cause the sharpened wedging tools to dislodge the coal in large pieces over an area extending entirely across the mine vein and cause the other tools to trim the floor and the roof adjacent the space from where the large pieces of coal are thus dislodged.

42. In a system of mining coal directly from the solid face of a mine vein, the method which consists in distributing a plurality of piercing wedging tools entirely across the working face of the mine vein each adapted to penetrate deeply the coal in its native state and by wedging action split large pieces of coal from the unmined mass, distributing trimming tools at the floor and at the roof of the mine chamber, applying a continuously acting, pushing force to all of said tools to position the same along the mine wall and applying hammer-blow wedging actions to said tools to dislodge the coal in large pieces and trim off the floor and the roof adjacent the spaces from where the coal is dislodged.

43. The long wall method of mining coal which consists in applying continuously forward hammer-blow pressure along the face of the mine vein in a general horizontal direction on a splitting tool to dislodge the coal between the floor and the roof of the mine chamber and at the same time applying similar dislodging actions along such face above

and below the space provided by the dislodgment of the intermediate portion to dislodge the coal from the upright mine wall near the floor and near the roof.

5 44. The long wall method of mining coal which consists in dislodging the coal from an upright face of a mine wall in a general horizontal direction along such face between the floor and the roof of a mine chamber by hammer-blown piercing and wedging and splitting actions, and also by similar action dislodging the coal from such mine wall along such face immediately above the floor and immediately below the roof while trimming the 10 roof and the floor to attain approximately horizontal surface.

45. In a system of mining coal directly from the solid of a mine vein, the method which consists in simultaneously piercing entirely by hammer-blown wedging action the unmined vein of coal in a mine substantially back from the face of an upright mine wall at spaced-apart points in an upright series and between the floor and the roof of the 20 mine chamber to split large slices of coal by such piercing and hammer-blown wedging action at such spaced-apart points with a minimum production of fine particles of coal.

46. In a system of mining coal, the method which consists in applying a piercing and wedging force by hammer-blown action horizontally back of the face of an upright mine wall intermediate the floor and the roof thereof to dislodge the intermediate section, 30 applying at spaced-apart points above and below such intermediate sections, piercing and wedging forces by hammer-blown actions back of the face of the mine wall to dislodge additional sections from such mine wall between such floor and roof.

47. The method of mining coal directly from the solid face of a mine vein in a mine chamber, which consists in applying simultaneously a plurality of piercing and wedging tools in spaced-apart relation across the 45 entire working face of the mine vein, and exerting hammer-blown forces on said tools in

general horizontal directions extending along the face of the mine vein to cause said tools to penetrate deeply into the solid face and split the coal in large pieces with a minimum production of fine particles by wedging action to effect dislodgment of the coal in such large pieces between said tools and over the entire area of the working face between the 50 approximately horizontal flat floor and the approximately horizontal flat roof of the mine chamber.

48. The method of mining mineral from the solid which consists in distributing a plurality of pointed wedging tools in an upright series each for concentration of dislodging action, and exerting a continuous forward horizontal rectilinear force on said tools to position the same along the face of the 55 mine vein, and exerting intermittent hammer-blown actions on said tools to cause the same to slice off a large area of the mineral in large pieces from the mine vein adjacent said tools and between the same and between the flat floor and the flat roof of the mine chamber with a minimum production of fine particles of mineral.

49. In a system of mining coal directly from the solid face of a mine vein in a mine 75 chamber, the method which consists in applying penetrating and hammer-blown actions at distributed points in an upright series extending across the face of the mine vein to tear the mineral in large pieces from the unmined mass over a wide area with a minimum production of fine particles of mineral.

50. In a system of mining coal directly from the solid face of a mine vein in a mine chamber, the method which consists in ripping away the native coal face over a wide area without blasting by applying penetrating wedging actions in an upright series distributed over such face and continuing such actions in the same direction, and applying 85 hammer-blown forces to secure deep penetration and wedging actions to dislodge the native coal in large pieces.

EDMUND C. MORGAN.
